UNITED STATES PATENT OFFICE.

GEORGE HALL, OF DETROIT, MICHIGAN, ASSIGNOR TO NELSON, BAKER & COMPANY, OF DETROIT, MICHIGAN, A CORPORATION OF MICHIGAN.

DESIGN FOR A BOTTLE-WRAPPER.

54,616.

Specification for Design.

Patented Mar. 9, 1920.

Application filed June 9, 1919. Serial No. 302,997. Term of patent 14 years.

To all whom it may concern:

Be it known that I, GEORGE HALL, a citizen of the United States of America, residing at Detroit, in the county of Wayne and State of Michigan, have invented a certain new, original, and ornamental Design for Bottle-Wrappers, of which the following is a specification, reference being had therein to the accompanying drawings, forming part thereof, in which—

Figure 1 is a front elevation of a bottle, showing my new design of wrapper; and Fig. 2 is a perspective view thereof, the bottle wrapper being shown in full lines and the bottle in the dotted lines.

I claim:

The ornamental design for a bottle wrapper, substantially as shown.

GEORGE HALL.
